(57) **ABSTRACT**

The drying apparatus includes a conveying belt and a heating unit. The heating unit includes a blower fan, a rectifying member, a heater, and a reflecting plate. The rectifying member is arranged on the downstream side of the blower fan in the blowing direction of the blower fan and includes one or more first through holes. The heater is arranged on the downstream side of the rectifying member in the blowing direction to radiate infrared rays in all directions. The reflecting plate is arranged between the rectifying member and the heater, includes one or more second through holes, and reflects the infrared rays radiated from the heater to the side of the conveying belt. The one or more first through holes are formed in a portion other than a portion where the infrared rays passing through the one or more second through holes of the reflecting plate are radiated.

DRYING APPARATUS AND IMAGE FORMING SYSTEM

INCORPORATION BY REFERENCE

This application is based upon and claims the benefit of priority from the corresponding Japanese Patent Application No. 2021-033614 filed on Mar. 3, 2021, the entire contents of which are incorporated herein by reference.

BACKGROUND

The present disclosure relates to a drying apparatus for drying a recording medium having an image formed thereon while conveying the recording medium, and an image forming system including the drying apparatus.

An image forming system including an inkjet type image forming apparatus is provided with a drying apparatus for drying an image formed on a recording medium such as paper. In a typical drying apparatus, a fan is provided on the back surface of the casing, and air taken in by the fan is blown from the side of the recording medium conveyed by the conveying unit.

However, when the air is blown from the side of the recording medium as in the case of the typical drying apparatus, the recording medium tends to float, and there is a possibility that a conveyance failure of the recording medium occurs.

An infrared heater may also be used in another typical drying apparatus. In order to efficiently dry the ink, it is effective to evaporate the moisture of the ink by blowing the air from the fan in addition to the infrared rays. Further, it is preferable to blow the air from above the recording medium to prevent the recording medium from floating when the recording medium is conveyed. Considering the above-description, the heater must be located downstream of the fan in the blowing direction of the fan.

When the infrared heater is arranged in this way, the infrared rays are also radiated from the infrared heater to the fan. Then, the parts of the fan may be heated and damaged.

SUMMARY

A drying apparatus of the present disclosure for drying a medium on which the image is formed while conveying the medium includes a conveying belt and a heating unit. The conveying belt supports the medium and conveys it in a predetermined conveying direction. The heating unit dries the image by blowing hot air on the medium. The heating unit includes a blower fan, a rectifying member, a heater, and a reflecting plate. The blower fan takes in outside air and blows air toward the conveying belt. The rectifying member is arranged on the downstream side of the blower fan in the blowing direction of the blower fan and includes one or more first through holes. The heater is arranged on the downstream side of the rectifying member in the blowing direction to radiate infrared rays in all directions. The reflecting plate is arranged between the rectifying member and the heater, includes one or more second through holes, and reflects infrared rays radiated from the heater to the side of the conveying belt. The one or more first through holes in the rectifying member are formed in a portion other than a portion where the infrared rays passing through the one or more second through holes of the reflecting plate are radiated among the infrared rays radiated from the heater.

An image forming system of the present disclosure includes an image forming apparatus for forming an image

2

on a medium, and a drying apparatus for drying the medium on which the image is formed by the image forming apparatus while conveying the medium. The drying apparatus includes a conveying belt and a heating unit. The conveying belt supports the medium and conveys it in a predetermined conveying direction. The heating unit dries the image by blowing hot air on the medium. The heating unit includes a blower fan, a rectifying member, a heater, and a reflecting plate. The blower fan takes in outside air and blows air toward the conveying belt. The rectifying member is arranged on the downstream side of the blower fan in the blowing direction of the blower fan and includes one or more first through holes. The heater is arranged on the downstream side of the rectifying member in the blowing direction to radiate infrared rays in all directions. The reflecting plate is arranged between the rectifying member and the heater and includes one or more second through holes for reflecting the infrared rays radiated from the heater to the side of the conveying belt. The one or more first through holes in the rectifying member are formed in a portion other than a portion where the infrared rays passing through the one or more second through holes of the reflecting plate are radiated among the infrared rays radiated from the heater.

BRIEF DESCRIPTION OF THE FIGURES

FIG. 1 is a perspective view schematically showing an image forming system according to an embodiment of the present disclosure.

FIG. 2 is a front view showing the inside of a drying apparatus according to the embodiment of the present disclosure.

FIG. 3 is a front view showing a heating unit, a conveying unit, and a suction unit of the drying apparatus according to the embodiment of the present disclosure.

FIG. 4 is an enlarged front view showing a part of a heating unit, a conveying unit, and a suction unit of the drying apparatus according to the embodiment of the present disclosure.

FIG. 5 is an enlarged perspective view showing a part of the heating unit, the conveying unit, and the suction unit of the drying apparatus according to the embodiment of the present disclosure.

FIG. 6A is a cross-sectional view showing the positional relationship between the through hole of a top plate and the through hole of the reflecting plate in the drying apparatus according to one embodiment of the present disclosure.

FIG. 6B is a sectional view illustrating the positional relationship between the through hole of the top plate and the through hole of the reflecting plate in the drying apparatus according to another embodiment of the present disclosure.

FIG. 7 is a plan view showing an example of the top plate of the drying apparatus according to an embodiment of the present disclosure.

DETAILED DESCRIPTION

An image forming system and a drying apparatus according to an embodiment of the present disclosure will be described below with reference to the figures.

First, an image forming system including a drying apparatus will be described with reference to FIG. 1. FIG. 1 is a front view showing an image forming system. L, R, Fr, and

Rr appropriately appended to each of the figures indicate left, right, front, and rear sides of the image forming system, respectively.

The image forming system 1 includes a paper feeder 3, an image forming apparatus 5, a drying apparatus 7, and a post-processing apparatus 9. The paper feeder 3 stores the paper and feeds the paper to the image forming apparatus 5. The image forming apparatus 5 is arranged on the left side of the paper feeder 3, and forms an image on the paper fed from the paper feeder 3 by an ink jet system. The drying apparatus 7 is arranged on the left side of the image forming apparatus 5, and dries the paper on which the image is formed while carrying the paper. The post-processing apparatus 9 is arranged on the left side of the drying apparatus 7, and performs post-treatment on the paper dried by the drying apparatus 7. Paper is an example of a recording medium.

Next, the drying apparatus 7 will be described with reference to FIGS. 2 to 5. FIG. 2 is a front view showing the inside of the drying apparatus, FIGS. 3 and 4 are front views showing a heating unit, a conveying unit, and a suction unit, and FIG. 5 is a perspective view showing a heating unit, a conveying unit, and a suction unit.

As shown in FIG. 2, the drying apparatus 7 includes a box-shaped casing 11. The casing 11 includes a rectangular parallelepiped hollow portion surrounded by a top plate, a bottom plate, front and rear side plates, and right and left side plates. A heating unit 13, a conveying unit 15 and a suction unit 17 are housed in the hollow portion on the side (right side) of the image forming apparatus 5. A cooling unit 19 is accommodated in the hollow portion of the casing 11 above the side (left side) of the post-processing apparatus 9.

A receiving portion 21 for receiving paper (medium) from the image forming apparatus 5 is formed on an upper portion of a right side plate (side plate on the side of the image forming apparatus 5) of the casing 11. A discharge portion 23 for delivering the paper to the post-processing apparatus 9 is formed on the left side plate (side plate on the side of the post-processing apparatus 9). The paper is conveyed by the conveying unit 15 and the cooling unit 19 along the conveying direction X from the receiving portion 21 to the discharge portion 23. In the following description, the upstream side and the downstream side respectively indicate the upstream side and the downstream side in the paper conveying direction X. A direction orthogonal to the conveying direction X is defined as a width direction.

Next, the heating unit 13 will be described. As shown in FIGS. 3 and 4, the heating unit 13 includes a plurality of blower fans 31, a heater unit 33, and a case 35 in which the plurality of blower fans 31 are supported and the heater unit 33 is housed.

The case 35 is formed in a box shape with an open lower side, and includes a hollow portion which is long in the conveying direction surrounded by an upper plate, front and rear side plates, and right and left side plates. A plurality of exhaust portions (not shown) (6 exhaust portions in this example) are formed on the upper plate. An exhaust fan 39 (see FIG. 2) is connected to each exhaust portion through a duct 37. By driving each exhaust fan 39, air in the case 35 is exhausted and the air in the hollow portion of the case 35 is circulated.

A plurality of blower fans 31 (12 blower fans in this example) are supported on the upper plate of the case 35. The plurality of blower fans 31 are so arranged that six fans are arranged in each of two rows along the conveying direction X. The distance between the blower fans 31 adjacent to each other in the conveying direction X and the width direction is substantially equal. The plurality of

blower fans 31 have the same air volume, take in outside air, and blow the taken outside air to the hollow portion of the case 35.

The heater unit 33 includes a plurality (24 heater units in this example) of infrared heaters 41, a plurality (24 heater units in this example) of reflecting plates 43, and a housing 45 in which the plurality of heaters 41 and the reflecting plates 43 are housed.

The housing 45 is formed in a box shape with an open lower side, and includes a hollow portion which is long in the conveying direction surrounded by the top plate 45a, front and rear side plates, and right and left side plates. As shown in FIG. 5, the top plate 45a includes a number of first through holes 51 formed in one surface. The plurality of first through holes 51 are arranged in a zigzag shape. The top plate 45a is an example of a rectifying member in which a large number of first through holes are formed, and rectifies the air taken into the case 35 by the blower fan 31 so as to be directed downward.

As shown in FIG. 4, each heater 41 includes, for example, a thin plate-like carbon filament 55 and a glass tube 57 in which the filament 55 is housed. Filament 55 radiates infrared rays in all radial directions (360°). The heaters 41 are arranged at equal intervals along the conveying direction X in an attitude along the width direction.

The reflecting plate 43 has a U-shape opening downward as viewed from the width direction, and includes a substantially rectangular upper wall and a sidewall bent downward at a substantially right angle from both long sides of the upper wall. A large number of second through holes 59 are formed in the upper wall. As shown in FIG. 5, the plurality of second through holes 59 are arranged in a zigzag shape with equal density. In this example, two second through holes 59 and three second through holes 59 are alternately arranged along the width direction. The reflecting plate 43 is disposed above the heater 41 and reflects downward the infrared rays radiated from the filament 55.

Next, the positional relationship between the first through hole 51 of the top plate 45a and the second through hole 59 of the reflecting plate 43 will be described with reference to FIGS. 6A, 6B, and 7. FIGS. 6A and 6B are cross-sectional views showing the positions of the first through hole 51 of the top plate 45a and the second through hole 59 of the reflecting plate 43. FIG. 6A shows three second through holes of the reflecting plate 43, and FIG. 6B shows two second through holes of the reflecting plate 43. FIG. 7 is a plan view showing a top plate.

As described above, the heater 41 radiates infrared rays in all directions (360°) in the radial direction. Infrared rays radiated upward from the heater 41 are reflected downward by the reflecting plate 43. However, since the second through hole 59 is formed in the reflecting plate 43, the infrared rays which have passed via the second through hole 59 among the infrared rays radiated upward are radiated upward, that is, toward the top plate 45a and the blower fan 31.

As described above, a number of first through holes 51 are formed in the top plate 45a. The first through hole 51 is formed in a portion other than a radiation surface from which the infrared rays are radiated to the top plate 45a via the second through hole 59 of the reflecting plate 43.

Specifically, as shown in FIG. 6A, in the case of three second through holes 59, the infrared rays passing via the second through holes 59L on the left side are radiated to the region R1 between the two dot-chain lines, the infrared rays passing via the second through holes 59C in the center are radiated to the region R2 between the two dot-chain lines,

and the infrared rays passing via the second through holes **59R** on the right side are radiated to the region **R3** between the two dotted lines. In this example, the radiation region **R1** and the radiation region **R3** of the adjacent heaters **41** intersect on the top plate **45a**.

In the case of two second through holes **59**, as shown in FIG. 6B, the infrared ray passing via the second through hole **59L** on the left side is radiated to the region **R4** between the two double-dotted lines, and the infrared ray passing via the second through hole **59R** on the right side is radiated to the region **R5** between the two dotted lines.

As shown in FIG. 7, the top plate **45a** includes a first through hole **51** formed in a portion other than the infrared radiation regions **R1**, **R2**, **R3**, **R4**, and **R5**. More specifically, as shown in FIG. 6A, a first through hole **51a** is formed between the radiation region **R3** and the radiation region **R2**, and a first through hole **51b** is formed between the radiation region **R2** and the radiation region **R1**. As shown in FIG. 6B, a first through hole **51c** is formed between the radiation region **R4** and the radiation region **R5**, and a first through hole **51d** is formed between the radiation region **R5** and the radiation region **R4**.

Next, the conveying unit **15** will be described. As shown in FIGS. 3 and 4, the conveying unit **15** includes a conveying belt **61** and a frame **63** for supporting the conveying belt **61**. The frame **63** includes front and rear side plates which are long in the conveying direction **X**, which are arranged at predetermined intervals in the front and rear directions. A drive roller **65** is rotatably supported between the upstream end units of the front and rear side plates, and a driven roller **67** is rotatably supported between the downstream end portions.

The conveying belt **61** is an endless belt, and a large number of through holes (not shown) are formed on the entire surface. The conveying belt **61** is wound around the drive roller **65** and the driven roller **67**. When the drive roller **65** is driven, the conveying belt **61** circulates in the counterclockwise direction in FIGS. 2 to 4. The outer surface of the conveying belt **61** along the upper track (in the direction from the upstream side to the downstream side) serves as the conveying surface **61a** on which the paper is conveyed. A conveying belt **61** traveling on an upper track is supported by conveying plates **69** supported by front and rear side plates. A through hole **71** (see FIG. 4) is formed on the entire surface of the conveying plate **69**. When the conveying belt **61** travels, the back surface of the conveying belt **61** (the back surface of the conveying surface **61a**) traveling on the upper track slides along the conveying plate **69**.

As shown in FIGS. 2 and 3, the conveying unit **15** is formed longer on the upstream side in the conveying direction **X** than the heating unit **13** is. More specifically, the upstream end of the conveying surface **61a** of the conveying belt **61** extends upstream from the upstream end of the heating unit **13** and upstream from the receiving portion **21**. The downstream end of the conveying surface **61a** is located at substantially the same position as the downstream end of the heating unit **13** and communicates with the cooling unit **19**.

Next, the suction unit **17** will be described. As shown in FIGS. 3 and 4, the suction unit **17** is provided in the hollow portion of the conveying belt **61**. The suction unit **17** includes a partition plate **83** and a plurality of (3 suction fans in this example) suction fans **85** supported by the partition plate **83**. The partition plate **83** includes a bottom plate and partition walls surrounding four sides, and as shown in FIG. 3, the hollow portion is divided into a plurality of (3 sections

in this example) sections **S1**, **S2**, **S3** along the conveying direction **X**. The upper surface of each section is opened to face the conveying plate **69**.

The suction fan **85** is attached to the bottom plate of the partition plate **83** corresponding to each section. The plurality of suction fans **85** have the same air volume. When the suction fan **85** is driven, the air in the space above the conveying belt **61** (conveying surface **61a**) moving on the upper track is taken into each section via the through hole of the conveying belt **61** and the through hole **71** of the conveying plate **69**.

An example of the drying operation of the drying apparatus **7** having the above configuration will be described with reference to FIGS. 2 to 5. The paper on which the image is formed by the image forming apparatus **5** (see FIG. 1) is received by the conveying unit **15** through the receiving portion **21** of the drying apparatus **7**. As described above, since the upstream end of the conveying surface **61a** of the conveying belt **61** extends to the upstream side of the receiving portion **21**, the paper discharged from the image forming apparatus **5** is placed on the conveying surface **61a** of the conveying belt **61**.

In the conveying unit **15**, the drive roller **65** is driven to rotate, and the conveying belt **61** travels. Thus, the paper placed on the conveying surface **61a** is conveyed into the casing **11** through the receiving portion **21**.

Further, the blower fan **31** of the heating unit **13** and the heater unit **33** are driven. The air taken into the hollow portion of the case **35** by the intake fan **31** is blown downward. The air enters the housing **45** through the first through hole **51** formed in the top plate **45a** of the housing **45** of the heater unit **33** (see arrow **A1** in FIG. 4). In the housing **45**, the infrared rays are radiated from each heater **41** in all directions by driving the heater unit **33**. The infrared rays radiated upward from the heater **41** are reflected downward by the reflecting plate **43**.

Here, the first through hole **51** (**51a**, **51b**, **51c**, and **51d** in FIGS. 6A, 6B, and 7) is formed in a portion of the reflecting plate **43** other than the region where the infrared rays passing via the second through hole **59** are radiated to the top plate **45a**. Therefore, the infrared rays radiated upward from the heater **41** via the second through hole **59** of the reflecting plate **43** are blocked by the top plate **45a**.

The air entering the housing **45** is blown further downward via the second through hole **59** of the reflecting plate **43** of the heater unit **33** (see arrow **A2** in FIG. 4) and heated by the infrared rays radiated from the heater **41**. The air thus heated is blown onto the paper conveyed along the conveying surface **61a** of the conveying belt **61** to dry the ink. Further, the paper is pressed against the conveying surface **61a** by the blown air.

Further, the suction fan **85** of the suction unit **17** is driven. As a result, as described above, the air in the space above the conveying belt **61** moving on the upper track is taken in through the respective sections through the through holes of the conveying belt **61** and the through holes **71** of the conveying plate **69** (see arrow **A3** in FIG. 4), and the pressure above the conveying surface **61a** becomes negative. Then, the paper conveyed on the conveying surface **61a** of the conveying belt **61** is attracted to the conveying surface **61a**.

When the paper is conveyed along the conveying surface **61a** from the upstream side to the downstream side, the ink is dried by the heating unit **13**.

While the paper is conveyed on the conveying surface **61a**, the inside of the case **35** of the heating unit **13** and the inside of the housing **45** of the heater unit **33** become an

environment of high humidity and high temperature, so that the exhaust fan 39 (see FIG. 1) is driven to circulate the air.

The paper conveyed along the conveying surface 61a to the downstream side is conveyed to the cooling unit 19 (see FIG. 1), cooled by the cooling unit 19, and conveyed to the post-processing apparatus 9 (see FIG. 1) through the discharge portion 23.

As is clear from the above description, according to the drying apparatus 7 of the present disclosure, the first through hole 51 (51a, 51b, 51c, and 51d in FIGS. 6A, 6B, and 7) is formed in a portion other than the region where the infrared rays passing via the second through hole 59 of the reflecting plate 43 are radiated to the top plate 45a, among the infrared rays radiated upward from the heater 41. That is, since the infrared rays radiated upward from the heater 41 via the second through hole 59 of the reflecting plate 43 are blocked by the top plate 45a, the amount of the infrared rays radiated upward toward the blower fan 41 through the first through hole 51 of the top plate 45a can be reduced. Therefore, damage to the blower fan 41 due to heating can be suppressed.

Since the first through hole 51 is formed in the top plate 45a in a region other than the infrared radiation region where the infrared rays passing via the second through hole 59 of the reflecting plate 43 are radiated, the air volume for drying 25 the medium can be secured.

According to the present disclosure, since the infrared ray radiated upward from the heater via the second through hole of the reflecting plate is blocked by the rectifying member, the amount of the infrared ray radiated upward toward the 30 blower fan can be reduced. Therefore, damage to the blower fan due to heating can be suppressed.

Although the present disclosure has been described for specific embodiments, the present disclosure is not limited to the above embodiments. Without departing from the 35 scope and spirit of the present disclosure, the foregoing embodiments may be variously modified, substituted, or modified, and the claims include all embodiments that may be included within the scope of the technical idea.

40

What is claimed is:

1. A drying apparatus for drying a medium on which an image has been formed while conveying the medium, the drying apparatus comprising:
  - a conveying belt that supports the medium and conveys the medium in a predetermined conveying direction; and
  - a heating unit that dries the image by blowing hot air onto the medium,
  - the heating unit including:
    - a blower fan that takes in outside air and blows air toward the conveying belt;

a rectifying member that is arranged on a downstream side of the blower fan in a blowing direction of the blower fan and includes one or more first through holes;

a heater that is arranged on a downstream side of the rectifying member in the blowing direction and radiates infrared rays in all directions; and

a reflecting plate that is arranged between the rectifying member and the heater, includes one or more second through holes, and reflects the infrared rays radiated from the heater toward the conveying belt,

wherein the one or more first through holes in the rectifying member are formed in a portion other than a portion where the infrared rays passing through the one or more second through holes of the reflecting plate are radiated among the infrared rays radiated from the heater.

2. An image forming system comprising:
    - an image forming apparatus that forms an image on a medium; and
    - a drying apparatus that dries the medium on which the image has been formed by the image forming apparatus while conveying the medium;
    - the drying apparatus including:
      - a conveying belt that supports the medium and conveys the medium in a predetermined conveying direction; and
      - a heating unit that dries the image by blowing hot air onto the medium,
      - the heating unit including:
        - a blower fan that takes in outside air and blows air toward the conveying belt;
        - a rectifying member that is arranged on a downstream side of the blower fan in a blowing direction of the blower fan and includes one or more first through holes;
        - a heater that is arranged on a downstream side of the rectifying member in the blowing direction and radiates infrared rays in all directions; and
        - a reflecting plate that is arranged between the rectifying member and the heater, includes one or more second through holes, and reflects the infrared rays radiated from the heater toward the conveying belt,
- wherein the one or more first through holes in the rectifying member are formed in a portion other than a portion where the infrared rays passing through the one or more second through holes of the reflecting plate are radiated among the infrared rays radiated from the heater.
